UNITED STATES PATENT OFFICE.

CHARLES A. BARTLETT AND LYMAN H. EASTMAN, OF CAMPBELL, NEBRASKA; SAID EASTMAN ASSIGNOR OF HIS RIGHT TO HENRY ERICKSON, OF CAMPBELL, NEBRASKA.

JAR-HOLDER.

1,384,176.

Specification of Letters Patent. Patented July 12, 1921.

Application filed August 11, 1919. Serial No. 316,826.

To all whom it may concern:

Be it known that we, CHARLES A. BARTLETT and LYMAN H. EASTMAN, citizens of the United States, residing at Campbell, in the county of Franklin and State of Nebraska, have invented new and useful Improvements in Jar-Holders, of which the following is a specification.

This invention relates to improvements in jar holders and aims to provide a jar holder of simple and durable character, which will tightly grip and hold a jar.

Another object of the invention is the provision of a jar which may be quickly adjusted to jars of different diameters.

Another object is the provision of a jar of this character, which will remain in a gripping position until manually released.

A further object is the provision of a holder, by means of which heated jars may be handled without danger of injury to the holder, due to the breaking of the jars.

Other objects and advantages of the invention will appear as the following description is read in connection with the accompanying drawings.

In the drawings:

Figure 1 is a top plan view of a jar holder embodying the present invention, the said view illustrating by dotted lines the position of the locking lever when the holder is in use.

Fig. 2 is an edge view of the same.

Referring in detail to the drawings, wherein like characters of reference denote corresponding parts, the holder as illustrated comprises a gripping band, 10, which is preferably formed of a strip of resilient metal and has secured to and projecting from one end a rigid handle 11. The opposite end of the band 10 has secured to and projecting laterally therefrom, a plate 12, to which is pivotally secured, as indicated at 13, a locking lever 14.

Secured to the end of the gripping band 10, which carries the handle 11, is one end of an adjusting element, preferably in the form of a chain 14^a, this chain being adapted to engage a notch or slot 15, formed in a lug 16, secured to and extending laterally from the lever 14, the links of the chain being adapted to engage the edges of the notch 15, so that the diameter of the band

10 may be regulated. For the purpose of limiting the movement of the lever 14 in one direction, the plate 12 carries a stop 17, which is adapted to engage one edge of the lever.

The band 10 is provided with a compressible lining in the form of a pad 18, which may be of any suitable material.

In the use of the invention, the band 10 is adjusted around the outside of a jar, or other receptacle, by means of the chain 14^a, whereupon the lever 14 may be swung upon its pivot in the position shown by dotted lines in Fig. 1, the lever then being upon the opposite side of the center of the direct pull of the chain, so that it will remain in this position until manually released. The holder will thus be secured upon the jar against accidental displacement, while the lining 18 will prevent any tendency of the band to break the holder. Should such breakage occur, due to the heated contents of the jar, the handle 11 and lever 14 are of sufficient length to prevent injury to the operator. In addition to providing means for positioning the holder from the jar, the handle permits of the jar being used after the manner of a dipper to facilitate filling.

The invention is susceptible of various changes in its form, proportions and minor details of construction and the right is herein reserved to make such changes as properly fall within the scope of the appended claim.

Having described the invention, what is claimed is:

A jar holder of the class described comprising a resilient metal gripping band, a rigid handle secured to and projecting from one end thereof, a plate secured to and projecting laterally from the opposite end of said band, a locking lever, pivotally secured to said plate, an adjusting element secured to one end of said band, a lug extending laterally from the lever and said lug having a slot formed therein to receive said adjusting element, and a stop carried by said plate to engage one edge of said lever.

In testimony whereof we affix our signatures.

CHARLES A. BARTLETT.
LYMAN H. EASTMAN.
